BED PLATE

Albert J. Allison, Dayton, Ohio, assignor to
Simonds Worden White Company, Dayton,
Ohio, a corporation of Ohio

Application February 24, 1932, Serial No. 594,796

4 Claims. (Cl. 92—22)

This invention relates to bed plates for use in beating engines, such as are used in the preparation of "stuff" (pulp) for making paper.

Beating engines and bed plates for beating engines being well known, it is needless at this time to describe either further than to explain the particulars wherein my improved bed plate differs from others.

While my bed plate, in common with most other bed plates, comprises a plurality of metal bars assembled into a unit, my plate differs from others in that the spaces between the bars are filled with an abrasive material, where others are filled with strips of wood, or, as in some cases, the spaces between the bars are left unfilled. With this brief preface I shall proceed to describe my improved bed plate in detail, with the aid of the accompanying drawings, in which

Fig. 1 is a plan view of one form of my improved bed plate;

Fig. 2 is an elevational view of the plate, with a portion of the outer bar removed;

Fig. 3 is transverse sectional view;

Fig. 4 is a fragment of one of the corrugated bars;

Fig. 5 is a plan view of another form of my improved bed plate;

Fig. 6 is an elevational view with part of one outside bar removed;

Fig. 7 is a sectional end elevation, and

Fig. 8 is a fragment of one of the corrugated bars.

Referring first to Figs. 1 to 3 it is seen that the bed plate is built up with a plurality of metal bars 10, separated by square blocks or washers 11. On each side of this group of bars 10 is a bar 12, the entire structure being united by bolts 13. The spaces 14 between the bars 10 are filled with an abrasive material, as will be more fully explained presently.

As shown in Fig. 1, this bed plate has a bend at its center, with the result that the bars of the beater roll with which this bed plate cooperates will first engage the ends of the bars 10, the points of contact gradually moving toward the center or apex of the bars. It is also to be noted that the portion of each bar 10 above the washers 11 is corrugated, making the upper edges of the bars 10, and the spaces 14 between them, sinuous in form. The idea of bending a bed plate as here shown is not new, but it has a special function here in that it prevents bars in the beater roll from coming into direct contact with the abrasive filling in the spaces 14. This point will be referred to further presently.

After the metal parts of my bed plate are assembled the spaces 14 are filled with an abrasive compound substantially the same as is used in making grinding wheels. The bars 10 are hardened by heat treatment, and for this reason I use an abrasive compound that can be hardened at a temperature which will not destroy the heat treatment of the bars. While there are various compositions that would answer the purpose I have obtained satisfactory results with granular aluminum oxide bonded with one of the well known synthetic resins, Redmanol, for example. This resin can be hardened at 350° F., which temperature will not affect the hardened metal bars. A mixture of aluminum oxide and Redmanol is pressed into the spaces, after which the bed plate is baked in an oven long enough to convert the resin into a hard insoluble bond. Preferably the bars 12 are not hardened. The advantage of this is that the first bar in the ensemble, that is, the bar the fly bars in the beater roll first engage, quickly wears to a shape best adapted to its function, so it can ease the fly bars onto the hardened bars of the bed plate. As it is not always certain which of the bars 12 will be the first, in the case of straight bed plates for instance, this depending upon which way the bed plate is put in the machine, both bars 12 are left unhardened.

Usually the active part of a bed plate is the bars, and an important function of the bars is to cut and bruise the fibers of the stock. In my improved bed plate the abrasive filling is the more important active element and its action upon the fibers is called "brushing" or "brooming", these being terms well established in the art. The abrasive element is protected from the bars of the beater roll by the hardened bars 10, while the beater bars drag the stock across the abrasive surfaces. As is seen in Fig. 3, the abrasive elements soon wear to a level slightly below the edges of the bars, forming a condition which produces a very desirable effect on the stock. The proximity of the abrasive elements to the bar edges restricts without wholly preventing the bars cutting and bruising the fibers, while the bars serve to break up bunches of fibers, thereby exposing individual fibers to the action of the abrasive elements.

I shall now describe the structure shown in Figs. 5 to 8. In this construction I use hardened steel bars 20, which are corrugated from edge to edge. By corrugating contiguous bars oppositely and placing opposed corrugations in contact, a plurality of approximately diamond shaped cells is formed. On each side of the

group of corrugated bars I place a clamping bar 21, the whole being bound together with bolts 22. I fill the cells 23 with an abrasive compound such as has already been described.

Obviously, all that I have said regarding the purpose and operation of the structure shown in Figs. 1 to 4 is applicable to the structure shown in Figs. 5 to 8. One additional difference in the two structures is to be noted, however, namely, that the latter is straight. This difference is not fundamental though, as the cellular structure can be built into a bent plate, while the structure shown in Figs. 1 to 4 may be made straight if desired. In the latter case the corrugations should be made deeper, so that the corrugations of one bar will extend into the spaces between corrugations in the contiguous bar, thereby preventing the bars of the beater roll getting into spaces between the bars 10 of the bed plate.

While I have shown only two forms of my invention it is not to be thought the invention is limited to these, as various modifications thereof are possible. For example, in the structure shown in Figs. 1 to 4 the square blocks 13 might be replaced by strips of metal as long as the bed plate, having bolt holes spaced to correspond to the holes in the bars 10 and 12. These strips would form bottoms for the spaces 14, making it unnecessary to fill the lower portions of the spaces with abrasive material. As anyone skilled in the art could make this change from the foregoing description, it is deemed unnecessary to illustrate the suggested modification. Having fully described my invention, and described two embodiments thereof, what I claim and desire to protect by a patent is as follows:

1. A bed plate comprising a plurality of hardened steel bars set on edge and assembled with spaces between them, an unhardened bar on each side of the unit thereby formed, and abrasive material whereby said spaces are filled. 5

2. A bed plate comprising a plurality of metal bars set on edge and assembled with spacers between them, whereby said plates are maintained in separated relationship, said bars being flat, save the upper portion of each bar, which is corrugated so the upper edges of the bars are sinuous in form, the spaces between said bars being filled with abrasive material. 10

3. A bed plate comprising a plurality of steel bars set on edge and assembled with spacers between them, whereby said plates are maintained in separated relationship, said bars being flat, save the upper portion of each bar, which is corrugated so the upper edges of the bars are sinuous in form, said bars being hardened by 15 heat treatment, the spaces between the bars being filled with abrasive material comprising a synthetic bonding material capable of being hardened in situ by means of heat at a temperature below that which will affect the heat treatment of the bars. 20

4. A bed plate comprising a plurality of hardened steel bars set on edge and assembled with spaces between them, an unhardened bar on each side of the unit thereby formed, and abrasive 30 material whereby said spaces are filled, said material comprising a synthetic bonding material capable of being hardened in situ with heat at a temperature below that which will affect the hardness of the hardened steel bars. 35

ALBERT J. ALLISON.
